COMBINED ESCUTCHEON PLATE AND DOORKNOB

Roy Stuart Denker, South Pasadena, Calif., assignor to
Schlage Lock Company, a corporation

Filed Sept. 7, 1962, Ser. No. 71,603

Term of patent 14 years

(Cl. D50—3)

FIG. 3

FIG. 4

FIG. 1

FIG. 2

FIG. 5

FIG. 1 is a front elevation of a combined escutcheon plate and doorknob showing my new design.

FIG. 2 is a side elevation.

FIG. 3 is a top plan view.

FIG. 4 is a cross section taken along lines 4—4 of FIG. 1.

FIG. 5 is a horizontal view taken along line 5—5 in FIG. 1 of the knob member.

I claim:

The ornamental design for a combined escutcheon plate and doorknob, as shown.
